UNITED STATES PATENT OFFICE.

CHARLES H. ARMSTRONG, OF BRIDGEPORT, CONNECTICUT.

ATTACHABLE RATCHET FOR DIE-STOCKS.

1,106,535.

Specification of Letters Patent. Patented Aug. 11, 1914.

Application filed September 29, 1913. Serial No. 792,263.

To all whom it may concern:

Be it known that I, CHARLES H. ARMSTRONG, citizen of the United States, and resident of Bridgeport, in the county of

5 Fairfield and State of Connecticut, have invented certain new and useful Improvements in Attachable Ratchets for Die-Stocks, of which the following is a specification.

10 This invention relates to new and useful improvements in attachable ratchets for die-stocks whereby the same may be operated by a single lever connection and by short movements of the same, as for instance in 15 close quarters where there would not be room to permit of a complete rotary movement of the die-stock and its regular handle connections.

It is the object of my invention to provide 20 a ratchet for the above purposes which will be adapted for attachment to several different styles of commercial types of die-stocks and especially those manufactured by me; to design the ratchet so that it can be 25 inexpensively manufactured and easily connected with or disconnected from the die stock, as occasion may require; and further so that it may be used permanently together with the complete stock, or periodically as 30 desired.

The invention further resides and consists 35 in the construction and novel combination and arrangement of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the 40 invention.

Similar characters of reference denote like or corresponding parts throughout the several figures of the accompanying two sheets of drawings forming a part of this specification, and upon which,

Figure 1, shows a plan view of my improved form of attachable ratchet as it would appear when applied to a die stock of the kind referred to. Fig. 2, is a side elevation of the said ratchet and stock. Fig. 3, is a transverse vertical cross section taken on line 3—3 of Fig. 1. Fig. 4, is a detached 55 plan view of a circular form of notched

disk as employed in my ratchet shown in the preceding figures, and, Fig. 5, is a detached side view of the pawl shown in Figs. 1, 2 and 3.

Referring in detail to the characters of reference marked upon the drawings 6 represents the die stock as a whole, 7 the oppositely disposed attached handles whereby the stock is rotated as in the cutting of a thread.

8 represents the two cutting dies that are 65 adjustably mounted in the stock and secured in said adjusted position by means of screws 9 and 10. The stock is further provided with a bushing 11 which is secured in the centrally arranged round hole through the 70 top of the stock so that said bushing will serve as a guide to support the pipe or rod while being threaded. This bushing is made attachable and can be replaced by another 75 different size bushing for guiding a different size of work through the die.

As will be noted the body of the die stock includes a pair of centrally arranged longitudinally disposed flanged ribs 12 that extend out upon each side of the body of the 80 stock to strengthen and stiffen the structure. A centrally arranged and upwardly disposed hub portion 13 is formed on the top side of the body, through which the before mentioned hole is formed and in which the 85 said bushing 11 is seated.

My improved ratchet comprises a fixed ring like member 14 whose lower annular edge portion is cut away to form lugs 15 and notches 16 to accommodate the ribs of the 90 body of the die stock so that the said lugs may be shouldered against the upwardly and centrally disposed ribs 17 formed on the die stock and on the opposite sides of the upwardly disposed annular portion 13 of said 95 stock. The upper portion of this ring member 14 is extended outward to form a flange that is finished and provided with a series of radially disposed notches 18 that are engaged by the vertically disposed pawl 19 seated in a pocket 20 of the handle portion 21 of the operating member 22. A spring 23 is seated in said pocket to engage and operate the pawl 19 and cause the same to engage the respective notches 18 of the disk 100 with each operation of the ratchet. The said handle portion 21 of the operating member 22 of the ratchet is provided with a threaded socket for the attachment of an operating handle, not shown. An annular recess 24 is 110

formed in the under side of this operating member to receive the flange portion of the fixed ring member 14. A plate 25 is secured to the annular under edge portion of said 5 operating member by means of screws 26 in a manner to overlap and engage the under face of the flange of the fixed member so that said operating member may be rocked or turned upon the said fixed member subject to the action of the engaging pawl. The 10 engaging end of the pawl 19 is beveled upon one side only as will be noted from the detailed illustration thereof. This pawl when drawn up against the action of the spring is 15 free to be turned half around thus making the shouldered side of the same engage the opposite vertical side wall of the notches of the ratchet, and thus form a means for causing the ratchet to operate in either direction. 20 This obviously permits the die stock to be turned on a pipe in the cutting of a thread and then turned off for the detachment of the die stock.

The bushings before referred to may be inserted in the stock through the ratchet and are secured in position by means of the stop 25 secured to the top side of the ratchet by a screw 28, in a way to be extended down into the central opening of the ratchet 30 against the said bushing.

The ratchet is secured to the die stock by means of a pair of attached clamps 29, one of which is secured to each side of the fixed member of the ratchet by means of removable screws 30 and is provided with a hook 35 like portion that extends cut around and in under the before mentioned ribs 12 of the die stock in a way to firmly secure and fix the member 14 to the said stock and so as to 40 insure the positive connection and operation of the two. In practice the ratchet is connected and disconnected entirely by means of these clamps, though in the operation of the ratchet the lugs 15 before mentioned 45 serve to bear the strain of the operative connections and thus relieve the clamps in a measure of this strain.

Having thus described my invention what

I claim and desire to secure by Letters Patent is:—

1. In a ratchet of the class described the combination of a fixed member having an annular flange with a series of radially disposed notches therein, a detachable hook like clamp secured to said fixed member and adapted to engage a die stock for attachment thereto, a movable member operatively mounted upon the flange of the fixed member, a spring actuated pawl carried by the movable member and adapted to engage the notches in the flange of the fixed member. 55

2. In a device of the class described, the combination with a die stock having ribs, of a fixed member having notched hub portions to engage the ribs and an annular flange 65 with a series of radially disposed notches therein, a detachable hook like clamp secured to said fixed member and adapted to engage the ribs of the die-stock, a rotatable member operatively mounted upon the flange of the 70 fixed member, a spring actuated pawl carried by the movable member and adapted to engage the notches in the flange of the fixed member.

3. In a double acting ratchet of the class described, the combination with a die-stock 75 of a fixed member having notched hub portions to engage the die-stock and provided with an annular notched flange, a pair of oppositely arranged detachable hook like 80 clamps secured to the sides of the fixed member and adapted to engage other ribs of the die-stock, a rotatable member operatively mounted upon the flanged member, an adjustable spring actuated pawl carried by the 85 movable member to engage the notches in the flange of the fixed member and adapted to be set to operate the ratchet either forward or backward.

Signed at Bridgeport in the county of 90 Fairfield and State of Connecticut this 22nd day of September A. D., 1913.

CHARLES H. ARMSTRONG.
